DESIGN FOR A BED COUCH

Joseph Martin, New York, N. Y., assignor to United States Cabinet Bed Co., Brooklyn, N. Y., a corporation of New York

Application March 10, 1934, Serial No. 51,002

Term of patent 14 years

To all whom it may concern:

Be it known that I, JOSEPH MARTIN, a citizen of the Republic of Spain, residing in the borough of Manhattan, city, county and State of New York, have invented a new, original, and ornamental Design for Bed Couches, of which the following is a specification, reference being had to the accompanying drawing, forming a part thereof, in which

Fig. 2 is a front elevation thereof; and
Fig. 3 is an end elevation thereof.

I claim:

The ornamental design for a bed couch, as shown.

JOSEPH MARTIN.
